UNITED STATES PATENT OFFICE.

RUDOLF LOEB, OF JENKINTOWN, PENNSYLVANIA.

SEAM FOR SEWED ARTICLES.

1,187,075.

Specification of Letters Patent. Patented June 13, 1916.

Application filed June 12, 1913. Serial No. 773,275.

To all whom it may concern:

Be it known that I, RUDOLF LOEB, a citizen of the United States, and a resident of Jenkintown, Montgomery county, Pennsylvania, have invented certain Improvements in Seams for Sewed Articles, of which the following is a specification.

My invention relates to ornamentation effected by embroidery stitching, and comprises a seam for sewed articles, which in some instances may be circular and in which I am enabled to effect a novel form of ornamentation in the form of large eyelet embroidery.

A further feature of my invention consists in applying an additional row of short stitches to the larger stitches so as to over-edge or buttonhole the inner marginal edge of the seam, whether inclosing an eyelet or formed in the body of the fabric.

These and other features of my invention will be more fully described hereinafter, reference being had to the accompanying drawings, in which:

Figure 1, is a view of the obverse side of one form of seam, which may be circular, made in accordance with my invention; Fig. 2, is a view of the reverse side of the seam shown in Fig. 1; Fig. 3, is a cross sectional view of the seam shown in Figs. 1 and 2; Fig. 4, is a view of the obverse side of a further modification within the scope of my invention, and Figs. 5 and 6, are views of other forms of ornamental seams made in accordance with my invention.

In the formation of these seams, I employ a machine with a vibrating needle, which machine is equipped with mechanism for turning the work with respect to the machine while the needle of the same vibrates in a single plane and lays stitches in a radial direction with reference to a predetermined center. By this means I am able to form a seam, which may be circular, of raised stitches 1 radiating from a common center and surrounding an aperture 2, or a space 2^a of the fabric, which aperture or space may be of any suitable dimensions. Directly adjacent the edge of the aperture,

I may provide a series of short stitches 3, which stitches have the effect of overedging or buttonholing the margin of the aperture 2 or space 2^a, and these are employed in combination with the longer stitches forming the major portion of the seam.

In the structure shown in Fig. 1, the

stitches 1 are substantially the same length from the margin of the aperture 2 to the circular outline defined by the seam, with a series of shorter stitches 3 directly adjacent the margin of the aperture. These longer stitches have loops on the under side; one loop 4 extending radially and facing toward the center from which the stitches are laid, while the other loop 5 is also radial and faces away from the center from which the stitches radiate, and these under loops are caught by a single shuttle thread 6. The shorter threads may be formed simultaneously with or subsequently to the longer stitches, and also have radially disposed loops 4^a and 5^a caught by a single shuttle thread 6^a.

In the seam illustrated in Fig. 4, the radial stitches 1^a are gradually shortened in groups so as to give a flower like effect; each of said stitches, however, possessing the radially disposed loops on the under side of the fabric arranged in the same manner as indicated in Fig. 2; certain of said loops facing inwardly, and the others facing outwardly, and the whole caught by a single shuttle thread. This seam is also provided with the short edging stitches 3 directly adjacent the margin of the aperture encircled by the seam.

In Figs. 5 and 6, I have shown other forms of seams within the scope of my invention; Fig. 5 showing a seam with a plurality of long stitches 1^b spaced some distance apart and the over-edging or button-hole stitches 3^b following the margin of the aperture 2. In Fig. 6, I have shown a view with a similar set of long radial stitches spaced some distance apart and indicated at 1^c, with the over-edging stitches 3^c following the margin of the aperture 2; the said outer ends of the long stitches 1^c being further connected by short radially disposed stitches 3^c lying between the outer ends of the long radial stitches. In all instances, these stitches will have a plurality of loops on the reverse side of the fabric caught by single shuttle stitches.

I claim:

As a new article of manufacture, a circular embroidery seam consisting of a piece of material having a plurality of sets of radial stitches formed with continuous needle threads surrounding a space, one set of which stitches extend in straight radial lines continuously on the obverse from the

inner margin of the space to the outer periphery of the circular seam, while the stitches of the other set are shorter and are disposed upon and bind the inner margin of the seam, each of said sets of stitches forming loops on the reverse side of the fabric, some of which extend inward radially from the circumference of the circular seam, while others extend outward from the inner margin of the seam, the ends of the several loops on the reverse side of the fabric lying

adjacent to each other, and independent shuttle threads independently securing the loops of the several sets of stitches.

In testimony whereof, I have signed my name to this specification, in the presence of two subscribing witnesses.

RUDOLF LOEB.
